JESSE JACKSON, OF KOKOMO, INDIANA, ASSIGNOR TO THE GLOBE STOVE & RANGE COMPANY, OF KOKOMO, INDIANA.

DOOR CONSTRUCTION FOR HEAT-INSULATED CHAMBERS.

1,234,669.

Specification of Letters Patent.

Patented July 24, 1917.

Application filed May 3, 1915. Serial No. 25,585.

To all whom it may concern:

Be it known that I, JESSE JACKSON, citizen of the United States, residing at Kokomo, county of Howard, State of Indiana, have 5 invented certain new and useful Improvements in Door Constructions for Heat-Insulated Chambers, of which the following is a specification.

It is the object of my present invention to 10 provide a door construction for heat-insulated chambers, whereby the door will be a firm and rigid structure, but yet the heat-conducting paths in the door and in the frame will both be interrupted between in- 15 terior of the chamber to the exterior thereof, so that there will be less loss of heat from the chamber and the exposed parts will be cooler.

The accompanying drawing illustrates my 20 invention. Figure 1 is a front elevation of a door and associated parts of a frame of a device embodying my invention; and Fig. 2 is a section on the line 2—2 of Fig. 1.

The chamber 10 is formed within the wall 25 11, which is spaced from a supporting casing 12 by suitable heat-insulating material 13, of any desired character and thickness. The open end of the chamber 11 is provided with a flange 15 which is fastened by bolts 30 16 to a rabbeted inset portion 17 of the frame 12, but the flange 15 is separated from the inset portion 17 by a layer of heat insulation 18, such as sheet asbestos, the bolts 16 passing through this asbestos, but the as- 35 bestos serving to insulate the frame 12 from the wall 11 so that but little heat is conducted from one to the other. This chamber 10 may be the oven of a stove, or the chamber of a fireless cooker, or any other chamber 40 which requires heat insulated walls.

The casing 12 is provided with forwardly 45 projecting hinge lugs 20 which coöperate with the hinge lugs 21 on the frame 22 of a swinging door for the chamber 10. This frame 22 is in the form of a hollow rectangle, against the back of which bears a sheet metal plate 23. A second sheet metal plate 24 is spaced from the plate 23 to provide a space of sufficient thickness for suitable heat-insu- 50 lating material 25, which is conveniently kieselguhr. This heat insulating material is held in place and the plates 23 and 24 held in proper relative position by a clamping member 26, which extends around the edge 55 of the space occupied by said heat insulating

material and overlaps upon the rear of the plate 24, and is held in place by bolts 27 which extend through such over-lapping part and the plate 24 and heat insulating material 25 into rearwardly extending lugs 60 28 on the door frame 22. The forward edge of the clamping member 26 extends against a heat-insulating gasket 29, conveniently of wire woven asbestos, and clamps such gasket in place against the rear wall of the frame 65 22, the gasket projecting outward beyond the clamping member 26 so as to rest in the rabbet in the inset portion 27. This heat-insulating gasket 27 interrupts the heat path between the metallic clamping member 26 70 and the plate 24 on the one hand and the door frame 22 on the other. The door frame and the casing may be provided with any suitable clamping means for holding the door shut, such as the swinging handle 30 75 on the door and the downwardly extending finger 31 on the casing.

I claim as my invention:

1. A heat-insulated chamber having an inner wall, an outer frame, said wall and frame having registering openings, clamping means for connecting said inner wall and outer frame around said openings, a layer of heat-insulating material separating said inner wall and said frame around said 80 opening, and a door for projecting into such registering openings and closing the chamber.

2. A heat insulated chamber having an inner wall, an outer frame, said wall and frame having registering openings, a layer of heat-insulating material separating said inner wall and said frame around said opening, and a door for projecting into such 90 registering openings and closing the chamber.

3. A heat-insulated chamber, comprising a wall having an opening, a frame surrounding said opening, and a door removably projecting into said opening, said door comprising a front member which overlaps the edge of the opening, a rear plate, heat-insulating material between the front member and the rear plate, a clamping member which overlaps upon the rear plate and extends across the edge of the space occupied by said heat-insulating material, and a gasket of heat insulating material which is clamped between the front edge of said clamping member and the rear face of said front 100 105 110

member and projects between the coöperating portions of said frame around the opening and the overlapping front member of the door.

5 4. A heat insulated chamber, comprising a wall having an opening, and a door removably projecting into said opening, said door comprising a front member which overlaps the edge of the opening, a rear

10 plate, heat-insulating material between the front member and the rear plate and separating said parts, a clamping member which overlaps upon the rear plate and extends across the edge of the space
15 occupied by said heat-insulating material, and a gasket of heat-insulating material which is clamped between the front edge of said clamping member and the rear face of said front member.

20 ~ 5. A heat-insulated chamber, comprising a wall having an opening, and a door removably projecting into said opening, said door comprising a front member which overlaps the edge of the opening, a rear 25 plate, heat-insulating material between the

25 plate, heat-insulating material between the front member and the rear plate and separating said parts, a clamping member which overlaps upon the rear plate and extends across the edge of the space occupied
30 by said heat-insulating material, a gasket of heat-insulating material which is clamped between the front edge of said clamping member and the rear face of said front member, and bolts connecting said clamping member and the front member of the door.

6. A heat-insulated chamber having an inner wall, an outer frame, said wall and frame having registering openings, a layer of heat-insulating material separating said inner wall and said frame around said opening, and a door removably projecting into said opening, said door comprising a front member which overlaps the edge of the opening, a rear plate, heat-insulating

member between the front member and the rear plate, a clamping member which overlaps upon the rear plate and extends across the edge of the space occupied by said heat-insulating material, and a gasket of heat-insulating material which is clamped between the front edge of said clamping member and the rear face of said front member. 50

7. A heat-insulated chamber, comprising 55
a wall having an opening, and a door re-
movably projecting into said opening, said
door comprising a front member which
overlaps the edge of the opening, a rear plate
spaced from said front member, a clamping 60
member which overlaps upon the rear plate
and extends across the edge of the space be-
tween the rear plate and the front member,
and a gasket of heat-insulating material
which is clamped between the front edge of
said clamping member and the rear face 65
of said front member and projects between
the coöoperating portions of said frame
around the opening and the overlapping
front member of the door. 70

8. A heat-insulated chamber, comprising a wall having an opening, and a door removably projecting into said opening, said door comprising a front member which overlaps the edge of the opening, a rear plate spaced from said front member, a clamping member which overlaps upon the rear plate and extends across the edge of the space between the rear plate and the front member, and a gasket of heat-insulating material which is clamped between the front edge of said clamping member and the rear face of said front member. 75
80

In witness whereof, I have hereunto set my hand and seal in the presence of two witnesses. 85
